RAILWAY TRAFFIC CONTROLLING
APPARATUS

Paul N. Bossart, Cheswick, Pa., assignor to The
Union Switch & Signal Company, Swissvale,
Pa., a corporation of Pennsylvania

Application January 13, 1941, Serial No. 374,263

14 Claims. (Cl. 246—63)

My invention relates to railway traffic controlling apparatus, and more particularly to train carried train control apparatus responsive to coded alternating current.

Train carried train control apparatus responsive to coded alternating current has been largely standardized for use of alternating current of a frequency of the order of 100 cycles per second, such current being coded by being periodically interrupted at different code rates. The coded current is supplied to the track rails of a track section through apparatus controlled by traffic conditions in advance of the section and the code rates of 180, 120 and 75 interruptions per minute are those generally used to reflect clear, approach-medium and approach traffic conditions, respectively. In two-block three-indication systems the code rates of 180 and 75 only are required. Inductors are mounted on a train in inductive relation to the track rails to inductively pick up energy during each on period of the coded current and hence the received energy has the same frequency and code rate as the rail current. The train is provided with train control apparatus including a filter, an amplifier, a code following relay and decoding relays, and such train carried apparatus has been standardized and a great many are now in service. The apparatus is housed in a suitable weatherproof box or case mounted on the train. The external circuits are connected to the proper local circuits within the box at terminal posts placed at a suitable location in the box. The outside source of supply which is ordinarily the usual 32 volt train carried generator or battery, and the inductors are connected to distinctive properly identified terminals. A filter is included in the apparatus and is interposed between the terminals to which the inductors are connected and the amplifier and this filter are tuned sharply at 100 cycles per second or some preselected frequency of that order so that only energy corresponding to the coded track rail current is passed to the amplifier. The amplifier consists ordinarily of two stages of amplification each stage of which includes an electron tube and associated circuits. The amplifier and its associated circuits are designed for the use of alternating current of the frequency of the order of 100 cycles per second. The master code following relay and decoding transformer are built into the amplifier unit and the master code following relay pole changes the supply of direct current to the primary winding of the decoding transformer, to the secondary winding of which transformer the

decoding means is connected. Such decoding means comprises reactors and condensers necessary to tune the decoding relay circuits to frequencies corresponding to the respective code rates of the track circuit current. That is the decoding relay circuits are tuned to frequencies corresponding to 180, 120 and 75 code rates. As stated hereinbefore such train carried train control equipment has been standardized and many are in use.

Track sections of the order of 11,000 feet in length have been proposed for railway signaling systems in order to adjust the signal system to the required train braking distance for high train speeds. A track circuit for an 11,000 foot track section may not provide effective broken rail protection when alternating current of 100 cycles is used. In order to assure effective broken rail protection for a track circuit of 11,000 feet in length it is necessary to use alternating current of a relatively low frequency, that is, an alternating current of a frequency of the order of 20 cycles per second or less must be used to provide effective broken rail protection for track circuits 11,000 feet in length. It is to be noted, of course that direct current would provide the highest degree of broken rail protection. When energy is inductively transferred between the track rails and train carried inductors the frequency of the current determines in part the magnitude of the energy transferred.

In view of the above cited standardized apparatus and the necessity of using a relatively low frequency alternating current for long track sections, a feature of my invention is the provision of railway traffic controlling apparatus incorporating novel means wherewith alternating current of the frequency of the order of 20 cycles per second effectively influences standard train carried train control apparatus designed for response to alternating current of the frequency of the order of 100 cycles per second.

Another feature of my invention is the provision of train carried train control apparatus incorporating novel means for converting coded alternating current of a relatively low frequency into coded alternating current of a relatively high frequency with the coding of the low frequency current maintained for the high frequency current.

Again, a feature of my invention is the provision of a novel adapter which when introduced between present standardized train carried inductors and their respective terminal posts within the usual equipment box, practically no changes

are required for effectively operating the standard amplifier and associated circuits by a pre-selected relatively low frequency alternating current supplied to the track rails.

Still another feature of my invention is the provision of a novel and improved adapter comprising a frequency changer and amplifier together with a switching means wherewith one position of the switching means renders the adapter active and connects it between the inductors and the respective terminals of the standard equipment box, and another position of the switching means renders the adapter inactive and the inductors are connected directly to the respective terminals of the equipment box so that such train carried train control apparatus can be used with the present day track circuits provided with alternating current of the order of 100 cycles per second.

The above features of my invention, as well as other advantages thereof which will become apparent as the specification progresses, are attained according to my invention by providing a suitable box or case which can be readily installed adjacent the standard equipment box and mounting in this additional box a four-pole double-throw switch and an adapter, and which adapter includes a frequency changer and an amplifier. The present wire from the inductors to the respective equipment box terminal FT is moved over onto a present spare terminal which in the instant case is designated terminal FT1. A wire from terminal FT1 together with four wires from terminals B32, N32, TC and FT of the present equipment box are carried through the four-pole double-throw switch in such a manner that in one position of the switch the power supply terminals B32 and N32 are disconnected from the adapter and the wire to the FT1 terminal is connected to the wire from the FT terminal with the result that the adapter is inactive and the inductors are connected directly to the standard equipment with the net result that the apparatus is conditioned for use with present day 100 cycle alternating current. The other position of the switch applies power from the B32 and N32 terminals to the adapter and the adapter is energized and made active, the wire from terminal FT1 is connected to the input side of the adapter and the output side of the adapter is connected to the wire to terminal FT with the result the adapter is interposed between the train carried inductors and the standard equipment and converts coded alternating current of a preselected low frequency to coded alternating current of a frequency of the order of 100 cycles, which latter current is applied to the present standard equipment, the coding of the low frequency alternating current being reproduced in the 100 cycle alternating current.

I shall describe three forms of apparatus embodying my invention and shall then point out the novel features thereof in claims.

In the accompanying drawings, Figs. 1, 2 and 3 are diagrammatic views showing three different forms of apparatus each of which embodies my invention. In the different views like reference characters are used to designate similar parts.

Referring to Fig. 1, the reference characters 1a and 1b designate the track rails of a railway over which traffic normally moves in the direction indicated by an arrow and which rails are formed by the usual insulated rail joints into a track section D-E which section may be one section 75

of a series of consecutive sections of a signal system. I shall assume for the purpose of illustration that section D-E is of a length of the order of 11,000 feet to provide satisfactory train braking distance for high train speeds. The section D-E is provided with a track circuit including a source of alternating current connected across the rails at the exit end of the section and a track relay connected across the rails at the entrance end of the section. The immediate source of current for the track circuit of section D-E is a track transformer TD whose secondary winding 2 is connected across rails 1a and 1b at exit end D over wires 3 and 4 with a current limiting impedance 5 preferably interposed in wire 3. A primary winding 6 of transformer TD is connected to a source of alternating current such as a generator G over any one of several different circuits which circuits include contacts of a control relay SA, contacts of an approach control relay VD and contacts of a code transmitter or coder CT. The generator G would be driven by any suitable means not shown and would deliver current at a preselected frequency and in order to better understand the invention I shall assume generator G delivers current of a frequency of 23 cycles per second. It will be understood, of course, that my invention is not limited to the use of a 23 cycle alternating current and any relatively low frequency of the order of 20 cycles or less may be used, it having been found as stated hereinbefore, that alternating current of the order of 20 cycles per second or less gives satisfactory broken rail protection for a track circuit 11,000 feet in length. It is also to be understood that my invention is not limited to a track section 11,000 feet in length, but such length is used for the purpose of illustration. It is apparent that generator G may be located at some central power station and current transmitted therefrom to the track section D-E over a transmission line.

When control relay SA is picked up in a manner to shortly appear to close front contacts 7 and 8, and approach control relay VD is released, closing back contact 9, a circuit can be traced from terminal BX of generator G over back contact 9 of relay VD, front contact 7 of relay SA, primary winding 6 of transformer TD, front contact 8 of relay SA and to terminal CX of generator G, and alternating current is supplied to primary winding 6 and is supplied in turn to the track rails of section D-E. I shall assume that the current supplied to the track rails over the circuit just traced is of a normal relative polarity. When control relay SA is released and approach relay VD is also released, the above traced circuit includes back contact 10 of relay VD and is pole changed at back contacts 11 and 12 of relay SA and current of reverse relative polarity is supplied to the rails of section D-E. The current thus supplied to the rails of section D-E is in each case non-coded. Assuming for the time being that a train shown conventionally at TV does not occupy section D-E, then the alternating current supplied to the rails is effective to energize a track relay ETR having a winding 13 connected across the rails at the entrance end E of the section. Track relay ETR is a standard two element alternating current relay and hence when its winding 13 is energized by current of normal relative polarity a contact member 14 of the relay is held at the left-hand position as viewed in Fig. 1, and when winding 13 is energized by current of relative reverse po-

larity the contact member 14 is held at the right-hand position. Contact member 14 is biased to occupy a center position to engage a back contact 15 whenever winding 13 is shunted and deenergized. Approach control relay VD is controlled over an obvious line circuit including back contact 15 of relay ETR and it follows that approach control relay VD is normally deenergized, that is, when section D—E is unoccupied. When the section D—E is occupied so that track relay ETR is deenergized then approach control relay VD is energized and picked up.

Relay SA is governed by a track relay DTR for the section next in advance of section D—E, and which track relay is similar to track relay ETR of section D—E so that when the section next in advance is unoccupied relay DTR is energized at either normal or reverse relative polarity closing either left-hand contact 16 or right-hand contact 17 and relay SA is picked up, and when the section next in advance is occupied and track relay DTR is deenergized, then relay SA is deenergized and released.

The code transmitter CT may be any one of several well-known types and may be of the relay type having two code contact members 75 and 180 which are operated to engage contacts 75a and 180a, respectively, when an operating winding 18 of the code transmitter is energized, the arrangement being such that contact 180—180a is closed at the rate of 180 times per minute and contact 75—75a is closed at the rate of 75 times per minute. Operating winding 18 of coder CT is energized by current from generator G over an obvious circuit including front contact 19 of approach control relay VD. Consequently, when section D—E is unoccupied and approach relay VD is released, the code transmitter CT is inactive, and when section D—E is occupied and relay VD is picked up the code transmitter is energized and made active.

When section D—E is occupied causing relay VD to be picked up and the section next in advance is unoccupied causing relay SA to be picked up, alternating current of a frequency of 23 cycles per second coded at the 180 code rate is supplied to the rails of section D—E through transformer TD, the circuit for primary winding 6 of transformer TD extending from terminal BX of generator G over front contact 21 of relay VD, contact 180—180a of coder CT, front contact 7 of relay SA, primary winding 6 of transformer TD, front contact 8 of relay SA and to terminal CX of generator G. When the section next in advance is occupied so that relay SA is released, then alternating current from generator G coded at the 75 code rate is supplied to the track rails of section D—E through transformer TD, the circuit for primary winding 6 extending from terminal BX of generator G over front contact 21 of relay VD, contact 75—75a of coder CT, back contact 12 of relay SA, primary winding 6 of transformer TD, back contact 11 of relay SA and to terminal CX.

Train carried train control apparatus is provided for the train shown at TV and such apparatus comprises inductor 22 and 23, a standard amplifying and decoding means, and an adapter shortly to be described. The inductors 22 and 23 are mounted on the train TV ahead of the leading pair of wheels in inductive relation to the rails 1a and 1b, respectively, and are connected together in the usual manner so that electromotive forces induced therein due to cur-

rent flowing in the rails in opposite directions at any given instant add their effects.

The amplifying and decoding means is housed in a standard equipment box indicated by a rectangle EB and such apparatus is of the standard form and will be described only as required for a full understanding of my invention. At a proper location within the equipment box EB, circuit terminals are provided of which terminals B32, N32, TC, T2 and FT are shown in Fig. 1 along with a present spare terminal designated by the reference character FT1. A train carried 32 volt direct current generator or battery (not shown) outside of the equipment box 15 is connected to the power supply terminals B32 and N32 for the purpose of providing power to the circuits of the train control apparatus within the equipment box EB. One terminal of inductors 22 and 23 is connected to control terminal TC over wire 24. The other terminal of inductors 22 and 23 is in the standard form of apparatus connected to the control terminal FT over wire 25, but according to my invention, wire 25 is removed from terminal FT and is connected to the present spare terminal FT1. A filter F1 is included in the apparatus housed in the equipment box EB and is connected to terminals TC, T2 and FT. This filter F1 comprises a transformer T1 and two condensers 21 and 28. Condenser 21 is connected across secondary winding 26 of transformer T1 and condenser 28 is connected between terminals FT and T2 and a primary winding 44 of transformer T1 is connected between terminals TC and T2. The filter F1 is tuned to pass current of the frequency of the order of 100 cycles per second and I shall assume for the apparatus of Fig. 1 that filter F1 is tuned sharply to resonance at 92 cycles per second which is the frequency used at the present time in certain cab signal systems. The two stage amplifier includes tubes 2PJ and 1PJ each of which is a three element tube and the filaments 29 and 30 of which are connected in series across the power supply terminals B32 and N32 with resistors 31 and 32 interposed in the connection. Thus the tubes are normally heated and in an active condition. Secondary winding 26 and condenser 28 in multiple of filter F1 are connected across grid 33 and filament 29 of the first stage tube 1PJ. The plate circuit of tube 1PJ receives energy from the usual 300 volt dynamotor (not shown) but whose terminals are indicated at B300 and N300 and this plate circuit is coupled to the grid circuit of the second stage tube 2PJ through an interstage transformer T3. The plate circuit of the second stage tube 2PJ includes the 300 volt current source and a primary winding 34 of an output transformer T4 to whose secondary winding 35 a master code following relay MR is connected. The arrangement is such that when coded alternating current of 92 cycles per second is applied across terminals TC and FT it is passed by filament F1 and amplified at tubes 1PJ and 2PJ and relay MR is operated at a rate corresponding to the code rate of the alternating current. Relay MR when operated controls at its contact member 36 the supply of direct current to the two portions of primary winding 37 of a decoding transformer T5 so that an alternating electromotive force of a frequency corresponding to the rate at which relay MR is operated is induced in secondary winding 38 of transformer T5. The electromotive force thus induced in secondary winding 38

is applied to two decoding circuits one of which includes a reactor 39 and the other of which includes a condenser 40 and a reactor 41 in series. At least a portion of reactor 39 is connected to a relay LR through a rectifier 42 and at least a portion of reactor 41 is connected to a relay AR through a rectifier 43. The circuit including reactor 39 is non-tuned and hence relay LR is effectively energized and picked up when relay MR is operated at a rate corresponding to either the 75 or 180 code rate. The circuit including condenser 40 and reactor 41 is tuned to resonance at the frequency of the electromotive force induced in secondary winding 38 of transformer T5 when relay MR is operated at a rate corresponding to the 180 code rate and hence relay AR is effectively energized and picked up for the 180 code rate but not for the 75 code rate. Relays AR and LR are used to control suitable train control devices, such as a cab signal CS. The operating circuits of cab signal CS are selectively governed over contacts of relays AR and LR in the usual manner and which will be apparent from an inspection of Fig. 1.

The adapter is mounted in a box indicated by a rectangle AB and comprises a manually operable switch SW, a frequency changer and an amplifier. The switch SW is a four pole double throw switch, a first or top center pole of which is connected to terminal FT1 of equipment box EB over wire 47, a second and a third center pole are connected to terminals B32 and N32 of box EB over wires 45 and 46, respectively, and its fourth center pole is connected to terminal FT over wire 48, wire 48 being also connected to the first left-hand pole of the switch. The other left-hand poles of the switch are idle and the four right-hand poles are connected to circuits of the adapter as will shortly appear.

In Fig. 1, the frequency changer comprises two frequency doublers. Such frequency doublers may take any one of several forms and may be of the type consisting of a full wave rectifier and a transformer. Looking at Fig. 1, a full wave rectifier 49 has one input terminal connected to terminal TC of the equipment box EB over wire 50 and its other input terminal connected to the first or top right-hand pole of switch SW through a condenser 51. The output terminals of rectifier 49 are connected to primary winding 52 of a transformer T6 across whose secondary winding 53, a condenser 54 is connected. The condenser 51 is proportioned to tune inductors 23 and 22 when connected thereto to resonance at 23 cycles per second and secondary winding 53 is parallel tuned by condenser 54 to resonance at 46 cycles per second. It follows that when switch SW is thrown to its right-hand position inductors 22 and 23 are connected across the input terminals of rectifier 49 through condenser 51 and the 23 cycle electromotive force picked up by the inductors due to the coded rail current causes a 46 cycle electromotive force to appear across secondary winding 53 and condenser 54 due to the rectifying action of rectifier 49. Secondary winding 53 of transformer T6 is connected across the input terminals of a full wave rectifier 55 whose output terminals are connected to primary winding 56 of a transformer T7. A secondary winding 57 of transformer T7 is parallel tuned to resonance at 92 cycles per second by a condenser 58 and consequently when an electromotive force of 46 cycles per second is made to appear across the secondary winding 53 of trans-

former T6 it is rectified and an alternating electromotive force of 92 cycles per second is caused to appear across secondary winding 58 of transformer T7 due to the rectifying action of rectifier 55. This 92 cycle electromotive force appearing across secondary winding 57 is applied to the grid circuit of an amplifier electron tube 59, electron tube 59 being here shown as of the indirect heater type.

When switch SW is thrown to the right the power supply terminals B32 and N32 of equipment box EB are connected to a filament circuit and a plate circuit of tube 59. The filament circuit can be traced from terminal B32 over wire 45, second right-hand pole of switch SW, wire 60, filament 61 of tube 59, a resistor 62, wire 63, third right-hand pole of switch SW and wire 46 to terminal N32. The plate circuit for tube 59 branches from wire 60 of the previously traced filament circuit through primary winding 64 of a transformer T8, plate 65 and intervening tube space to cathode 66 of tube 59, and thence to wire 63 of the filament circuit. The primary winding 64 of transformer T8 is parallel tuned by a condenser 67 so that the 92 cycle electromotive force created across secondary winding 57 of transformer T7 is amplified at tube 59 and creates a corresponding electromotive force in secondary winding 68 of transformer T8, which secondary winding 68 serves as an output winding of the adapter. Output winding 68 is connected to the control terminals TC and FT of the standard equipment box EB through switch SW in the right-hand position. Starting at terminal FT this connection includes wire 48, fourth right-hand pole of switch SW, an impedance 70, wire 69, secondary winding 68, and wires 71 and 50 to the control terminal TC. Thus the 92 cycle electromotive force created in output winding 68 is applied to the standard amplifying and decoding means for operation thereof.

It is to be seen therefore that when switch SW is thrown to the left the adapter is inactive and the inductors 22 and 23 are connected directly to the control terminals TC and FT of the standard equipment box for operation of the train control apparatus by the electromotive forces picked up by inductors 22 and 23 as would be the case when the apparatus is used with 92 cycle alternating current track circuits. When switch SW is thrown to the right, the adapter is energized and the inductors 22 and 23 are connected to the input side of the adapter whose output side (secondary winding 68) is connected to the terminals TC and FT of the standard equipment box and the 23 cycle electromotive force picked up by the inductors 22 and 23 when the train occupies track section D—E is converted to coded alternating current of 92 cycles and this latter current is applied to the usual terminals TC and FT of the standard equipment box for operation of the standard amplifying and decoding means.

It is to be observed that while in Fig. 1 the two frequency doublers of the adapter are arranged in cascade and the amplifier is placed in the output of the second frequency doubler, this order of these devices is immaterial and the amplifier can be placed ahead of the first frequency doubler or it may be interposed between such frequency doublers. It is also to be observed that if further increase in the frequency is required an additional frequency doubler can be included in the adapter.

In Fig. 2, the trackway portion of the appa-

ratus, the train carried inductors and the standard amplifying and decoding means are the same as in Fig. 1 and further description of this apparatus is not required. Also the manual operable switch SW placed in the adapter box AB is the same as in Fig. 1 and has its poles connected to terminals B32, N32, FT and FT' of box EB in the same manner as in Fig. 1.

In Fig. 2 an adapter including a magnetic bridge type amplifier and a generator is provided. When the switch SW of Fig. 2 is thrown to the right the inductors 22 and 23 are switched to a tuned inductor L2 through a condenser 12 which is proportioned to tune the inductors 22 and 23 and their connection to inductor L2 to resonance at the frequency of the track circuit current, that is, it is tuned to resonance at a frequency of the order of 20 cycles per second. A condenser 13 is connected across inductor L2 to tune the inductor to resonance at the frequency of the track circuit current. At least a portion of inductor L2 is connected to the input terminals of a full wave rectifier 14 and the output terminals of this rectifier are connected to an input winding consisting of coils 76a and 76b of a magnetic bridge type amplifier having two magnetic core structures A and B. Each core structure A and B is of a three-legged form and besides the input winding coils 76a and 76b mounted on the central leg of the cores A and B, respectively; two bridge arm windings consisting of two coils 77 and 78 mounted on the left-hand leg and right-hand leg of cores A and B, respectively, and two bridge arm windings consisting of two coils 79 and 80 mounted on the right-hand leg of core A and the left-hand leg of core B, respectively, are provided. A biasing winding consisting of two coils 81 and 82 is mounted on the center legs of the cores A and B and a source of direct current, such as a battery 83 is interposed in the circuit of the biasing winding to provide a predetermined initial direct current flux in the cores.

Alternating current of a frequency of the order of 100 cycles per second is supplied to the bridge windings 77, 78, 79 and 80 from a small generator GI, the arrangement being such that windings 77, 78, 79 and 80 are connected to form the well-known Wheatstone bridge arrangement. This structure of the magnetic amplifier is that covered by Letters Patent of the United States No. 1,824,577, granted September 22, 1931, to A. J. Sorensen for Electrical translating apparatus, and it is sufficient for the instant application to point out that input coils 76a and 76b are so connected that the flux created by current supplied from rectifier 14 aids the biasing flux created in core A by the current flowing in biasing winding 81 but opposes the biasing flux created in core B by current flowing in biasing winding 82. When no current flows in the input winding 76a-76b the bridge windings are balanced so that no current is supplied to a load winding 84 connected across the opposite corners of the Wheatstone bridge. When unidirectional current is supplied to the input winding 76a-76b the impedance of core A is varied in one direction due to the unidirectional flux created by the current flowing in coil 76a aiding the flux created by biasing winding 81, and the impedance of core B is varied to the opposite direction due to the unidirectional flux created by current flowing in input coil 76b opposing the biasing flux created by winding 82, and such variations of the impedances of cores A and B

unbalance the bridge with the result that 100 cycle alternating current is supplied to the load winding 84.

Consequently when coded alternating current of the frequency of the order of 20 cycles per second is picked up by inductors 22 and 23 due to the train occupying section D-E, such current is rectified at rectifier 14 and unidirectional current is supplied to the input winding of the magnetic amplifier during each on period of the code, and 100 cycle alternating current is supplied to the output winding 84, the coding of the 100 cycle alternating current being the same as the coding of the alternating current picked up from the track rails. The generator GI as shown in Fig. 2 is driven by a small motor 85 which is connected to the power supply terminals B32 and N32 of the equipment box EB when switch SW is thrown to the right. This circuit for motor 85 includes the second and third right-hand poles of switch SW as will be apparent from an inspection of Fig. 2. It is to be noted that instead of a motor generator consisting of a motor 85 and generator GI a vibration type of alternator may be used the operating winding of which would be connected to the power supply terminals in the same manner that motor 85 is connected thereto. It should also be noted that the biasing winding 81-82 which is supplied with current from battery 83 may be supplied with direct current from the power supply terminals B32 and N32 if desired.

The load winding 84 serves as a primary winding for a transformer T9, whose secondary winding 86 serves as an output winding for the adapter and is connected to the control terminals TC and FT of the standard equipment box EB over wires 48 and 50 and the fourth right-hand pole of switch SW. It is to be seen therefore that when switch SW of Fig. 2 is thrown to the left the inductors 22 and 23 are connected to the control terminals TC and FT the same as in present day practice and when switch SW is thrown to the right the adapter is energized and made active and is interposed in the connection between inductors 22 and 23 and terminals TC and FT of the standard equipment box.

With the apparatus of Fig. 2 the frequency of the current supplied by the adapter for operation of the standard train control apparatus housed in equipment box EB is not directly dependent upon the frequency of the track rail current. Thus the current supplied by the track rail apparatus of Fig. 2 may be any preselected frequency of the order of 20 cycles per second as will provide effective broken rail protection. The generator included in the adapter is set to deliver a current of the frequency at which the standard apparatus is tuned and in the instant case it is set to deliver current of a frequency of the order of 100 cycles per second.

Referring to Fig. 3, the trackway portion of the apparatus and the train carried amplifying and decoding means are the same as in Fig. 1. Also switch SW mounted in box AB is connected to terminals of the standard equipment box EB in the same manner as in Fig. 1. In Fig. 3 the adapter comprises a reactive transformer T10, a rectifier 87, a resistor R2, an electron tube oscillator OS and another reactive transformer T11. When switch SW of Fig. 3 is thrown to the right, a first winding 88 of transformer T10 is connected between terminals TC and FT' of the equipment box EB and hence is connected to the train carried inductors 22 and 23, as will be apparent

by an inspection of Fig. 3. A condenser 89 is interposed in this circuit connecting the inductors to winding 88 and is proportioned to tune the circuit to resonance at the frequency of the alternating current supplied to the track circuit of section D—E of Fig. 3. That is, this circuit including the inductors is tuned to resonance at a frequency of the order of 20 cycles per second or some preselected frequency that is effective to provide satisfactory broken rail protection. A condenser 90 is connected across a secondary winding 91 of transformer T10 to parallel tune secondary winding 91 to resonance at the frequency of the track circuit current. At least a portion of secondary winding 91 of transformer T10 is connected to the input terminals of rectifier 87 whose output terminals are connected across resistor R2. It follows that the electromotive force picked up by inductors 22 and 23 is rectified and a unidirectional current is supplied to resistor R2 causing a voltage drop across that resistor during each on period of the coded track circuit current. Hence the voltage created across resistor R2 has on and off periods substantially in step with the on and off periods of the track circuit current. Resistor R2 is preferably bypassed by a condenser 92 for reasons to shortly appear.

Oscillator tube OS may be of the indirect heater type, the filament 93 of which is connected to the power supply terminals B32 and N32 of equipment box EB when switch SW is thrown to the right over an obvious circuit including a current limiting resistor 94. The reactive transformer T11 has three windings. A first winding 95 of transformer T11 is included in the plate circuit of tube OS by one terminal of winding 95 being connected to the power supply terminal B32 over the second right-hand pole of switch SW, the other terminal of winding 95 being connected to the plate 96 of tube OS, and the cathode 97 of tube OS being connected to the power supply terminal N32 over the third right-hand pole of switch SW. A second winding 98 of transformer T11 is parallel tuned by a condenser 99 and the two in multiple are connected between control grid 100 and cathode 97 of tube OS, a blocking condenser 101 being interposed in the connection to control grid 100. Winding 95 included in the plate circuit supplies through secondary winding 98 the necessary feed back for oscillation and the tuning of winding 98 sets the frequency of the oscillations. Winding 98 and condenser 99 are proportioned to provide oscillations of a frequency of the order of 100 cycles per second. That is, the winding 98 and condenser 99 are proportioned to cause oscillations of a frequency corresponding to the frequency at which the associated standard train control apparatus is tuned. Resistor R2 is connected across control grid 100 and cathode 97 through a battery 102, and condenser 92 serves to by-pass resistor R2 to prevent the fundamental frequency of the energy picked up by the inductors 22 and 23 and its multiple frequencies so that such frequencies do not appear in the output of tube OS.

When no voltage is developed across resistor R2 the voltage of biasing battery 102 provides a negative grid bias voltage sufficient to cause substantially no plate circuit current and hence no oscillations are generated. The connection of resistor R2 is such that the voltage developed across resistor R2 during an on period of the coded energy picked up by inductors 22 and 23 drives grid 100 more positive in potential with

respect to cathode 97 so that plate circuit current flows and tube OS is set into oscillation. Hence the on and off periods of the oscillations developed by tube OS are substantially in step with the on and off periods of the coded energy picked up by inductors 22 and 23 and indirectly in step with the on and off periods of the coded track circuit current.

A third or output winding 103 of transformer T11 is connected across control terminals TC and FT of equipment box EB over the fourth right-hand pole of switch SW and hence when tube OS is caused to oscillate an electromotive force of a frequency corresponding to the frequency of the oscillations is induced in winding 103 and applied to control terminals TC and FT to cause operation of the standard amplifying and decoding apparatus.

It is to be seen therefore that when switch SW of Fig. 3 is thrown to the left, inductors 22 and 23 are connected directly to terminals TC and FT of the equipment box the same as in Figs. 1 and 2 and conditions the apparatus of Fig. 3 for operation over present day track circuits, and when switch SW is thrown to the right the adapter is energized and interposed in the connection between inductors 22 and 23 and the terminals TC and FT of the equipment box EB with the result that the coded energy of a relatively low frequency picked up by inductors 22 and 23 is converted into coded alternating current of a relatively high frequency suitable for operation of the standard amplifying and decoding means.

It should be noted in connection with Fig. 3 that biasing battery 102 may be omitted and grid 100 provided with no normal negative grid bias voltage so that when no voltage is developed across resistor R2 tube OS is caused to oscillate and produce a corresponding electromotive force in the output winding 103 of transformer T11 and which output electromotive force is applied to terminals TC and FT. Under such conditions resistor R2 is so connected that the voltage developed across the resistor during an on period of the energy picked up by inductors 22 and 23 drives grid 100 more negative in potential with respect to the cathode and the oscillations cease. With the apparatus of Fig. 3 thus arranged an inverse code would be applied to the standard amplifying and decoding means. Since the on and off periods of the coded track circuit current are substantially equal an electromotive force of an inverse code when applied to the standard amplifying and decoding means provides satisfactory operation thereof.

It is apparent that in each of the three different forms of apparatus embodying my invention, I have provided train carried train control apparatus incorporating an inexpensive adapter capable of being located in a separate box outside of the standard equipment box and which adapter is effective to make the standard amplifying and decoding means operable on coded alternating current of a relatively low frequency notwithstanding such amplifying and decoding means is designed and tuned for operation by coded alternating current of a relatively high frequency. Also the change-over of the train carried apparatus from a condition of response to coded alternating current of a relatively high frequency to response to coded alternating current of a relatively low frequency is accomplished by throwing a manually operable switch.

Although I have herein shown and described only three forms of railway traffic controlling

apparatus embodying my invention, it is understood that various changes and modifications may be made therein within the scope of the appended claims without departing from the spirit and scope of my invention.

Having thus described my invention what I claim is:

1. In railway traffic controlling apparatus for use with train carried amplifying and decoding means responsive to coded alternating current of a preselected relatively high frequency and which current is received through inductors mounted on the train in inductive relation to the track rails, the combination comprising, means to supply to the rails of a track section coded alternating current of a preselected relatively low frequency, and a frequency converting means interposed in the connection between said inductors and said amplifying and decoding means to convert said coded low frequency alternating current into coded alternating current of said preselected relatively high frequency.

2. In railway traffic controlling apparatus for use with train carried amplifying and decoding means responsive to alternating current of a preselected relatively high frequency coded at different preselected code rates and which current is received through inductors mounted on the train in inductive relation to the track rails, the combination comprising, means to supply to the rails of a track section alternating current of a preselected relatively low frequency coded at said different preselected code rates according to traffic conditions in advance of said section, and a frequency converting means interposed in the connection between said inductors and said amplifying and decoding means to convert said low frequency alternating current coded at any particular one of said code rates into alternating current of said preselected high frequency coded at a corresponding code rate.

3. In railway traffic controlling apparatus for use with train carried amplifying and decoding means responsive to coded alternating current of a preselected relatively high frequency and which current is received through inductors mounted on the train in inductive relation to the track rails, the combination comprising, means to supply to the rails of a track section coded alternating current of a preselected relatively low frequency, a frequency converting means adaptable of converting said low frequency alternating current coded at a particular code rate into alternating current of said preselected high frequency coded at said particular code rate, and switching means effective at one position to interpose said frequency converting means in the connection of said inductors to said amplifying and decoding means and effective at another position to connect said inductors directly to the amplifying and decoding means.

4. In railway traffic controlling apparatus for use with train carried amplifying and decoding means responsive to alternating current of a frequency of the order of 100 cycles per second coded at either a first or a second code rate and which current is received through inductors mounted on the train in inductive relation to the track rails, the combination comprising, means to supply to the rails of a section alternating current of the frequency of the order of 20 cycles per second coded at either said first or said second code rate according to traffic conditions in advance of said section, converting means adaptable of converting said 20 cycle alternating cur-

rent coded at either said first or said second code rate into 100 cycle alternating current coded at the corresponding code rate, and switching means effective at a preselected position to interpose said converting means in the connection of said inductors to said amplifying and decoding means.

5. In railway traffic controlling apparatus for use with train carried amplifying and decoding means tuned sharply to resonance at a frequency of the order of 100 cycles per second and adaptable of response to such current coded at either a first or a second code rate, the combination comprising, means to supply to the rails of a track section alternating current of a frequency of the order of 20 cycles per second coded at either said first or said second code rate according to a first or a second traffic condition in advance of said section, an inductor mounted on the train in inductive relation to the track rails to inductively receive when the train occupies said section a current of the frequency and code rate of that supplied to the rails of the section, a train carried adapter including a two-way switch and frequency converting means operative to convert alternating current of the frequency of the order of 20 cycles per second coded at either said first or said second code rate into alternating current of the frequency of the order of 100 cycles per second coded at a corresponding code rate, and said switch effective at a selected one of its positions to interpose said adapter between said inductor and said amplifying and decoding means.

6. In railway traffic controlling apparatus for use with train carried amplifying and decoding means responsive to coded alternating current of 100 cycles per second inductively received through an inductor mounted on the train in inductive relation to the track rails, the combination comprising, means to supply to the track rails of a track section coded alternating current of 20 cycles per second, a train carried frequency converter adaptable of converting current of 20 cycles to current of 100 cycles per second, and a manually operable double throw switch interposed in the connections of said inductor to the input terminals of said amplifying and decoding means to connect said inductor directly to said terminals in a selected one of the positions of the switch and to connect said inductor to said terminals through said frequency converter in the other position of the switch.

7. In railway traffic controlling apparatus for use with train carried train control equipment including an electron tube amplifier and a filter with the filter connected between the input terminals of such equipment and said amplifier, and which filter comprises inductances and capacitance tuned sharply to resonance at a preselected first frequency, the combination comprising, a track section, means to supply to the rails of the section alternating current of a preselected second frequency which is different from said first frequency, train carried inductors mounted on the train in inductive relation to the rails to receive an alternating current of said second frequency when the train occupies the section, a train carried adapter including frequency converting means effective to convert alternating current of said second frequency into alternating current of said first frequency, and switching means effective at one position to connect said inductors directly to the input terminals of said train control equipment and effective at another

position to connect said inductors to the input side of said adapter and the output side of the adapter to the input terminals of the train control equipment.

8. In combination with standard train carried train control apparatus including a filter tuned sharply to resonance at a preselected relatively high frequency and connected to designated terminals of an equipment box housing such train control apparatus, inductors mounted on the train in inductive relation to the track rails, trackway means to supply to the track rails of a track section alternating current of a preselected relatively low frequency as required to provide satisfactory broken rail protection for the section and to induce in said inductors an alternating current of said low frequency when the train occupies said section, a train carried frequency changer responsive to alternating current of said low frequency to create alternating current of said high frequency, a double throw manually operable switch, circuit means including a first position of said switch to connect said inductors to said designated terminals of the equipment box, and circuit means including a second position of said switch to connect said inductors to the input side of said frequency changer and the output side of the frequency changer to said designated terminals.

9. In combination with standard train carried train control apparatus including a filter tuned sharply to resonance at a frequency of the order of 100 cycles per second and connected to designated control terminals of an equipment box housing such train control apparatus and which box is provided with designated power supply terminals, trackway means to supply to the rails of a track section alternating current of a frequency of the order of 20 cycles per second to provide effective broken rail protection for that section, inductors mounted on the train to receive an electromotive force of a frequency the same as that of the rail current when the train occupies said section, a train carried adapter including a frequency changer and an amplifier made responsive to an electromotive force of a frequency of the order of 20 cycles per second when supplied by direct current to create an alternating current of a frequency of the order of 100 cycles per second, a double throw manually operable switch, and circuit means including a selected position of the switch to connect said power supply terminals and said inductors to said frequency changer and amplifier and to connect an output circuit of the amplifier to said control terminals.

10. In combination with train carried train control apparatus including a filter tuned sharply to resonance at 92 cycles per second and connected to designated control terminals of an equipment box housing such train control apparatus and which box is provided with designated power supply terminals, trackway means to supply to the rails of a track section 23 cycle alternating current to provide effective broken rail protection for that section, inductors mounted on the train to receive a 23 cycle electromotive force when the train occupies said section, a train carried adapter including a first and a second frequency doubler and an electron tube amplifier, said frequency doublers connected in cascade to convert a 23 cycle electromotive force into a 92 cycle electromotive force, said electron tube amplifier having its grid circuit connected to said second frequency doubler to amplify in its plate

circuit said 92 cycle electromotive force produced by said frequency doublers, a winding coupled to said plate circuit to receive energy due to such amplified 92 cycle electromotive force; and 5 switching means effective at a preselected position to connect said inductors to said first frequency doubler, to connect said power supply terminals to said amplifier tube and to connect said winding to said control terminals to operate 10 said train control apparatus in response to the energy received by said inductors.

11. In combination with train carried train control apparatus including a filter tuned sharply to resonance at 92 cycles per second and connected to designated control terminals of an equipment box housing such train control apparatus and which box is provided with designated power supply terminals, trackway means to supply to the rails of a track section 23 cycle alternating current to provide effective broken rail protection for that section, inductors mounted on the train to receive a 23 cycle electromotive force when the train occupies said section; a train carried adapter including a first and a second frequency doubler, an electron tube amplifier and an output winding; a manually operable switch, a first circuit means including a preselected position of said switch to connect said inductors and said power supply terminals to said adapter to convert the 23 cycle electromotive force received by the inductors into a 92 cycle electromotive force which is amplified and supplied to said output winding, and a second circuit means including said preselected position of the switch to connect said output winding to said control terminals to operate said train control apparatus by the electromotive force thus supplied to the output winding.

12. In combination with train carried train control apparatus tuned sharply to resonance at a preselected relatively high frequency and connected to designated control terminals of an equipment box housing such train control apparatus, trackway means to supply to the rails of a track section alternating current of a preselected relatively low frequency as required to provide effective broken rail protection, inductors mounted on the train to inductively pick up energy in response to such low frequency alternating current when the train occupies said section, a train carried adapter including a generator and a bridge type magnetic amplifier having a control input circuit and a bridge circuit and a load winding, said generator effective to supply alternating current of said high frequency to said bridge circuit, a manually operable switch, a rectifier, circuit means including a preselected position of said switch to connect said inductors to said control circuit through said rectifier to cause current to be supplied from the generator to said load winding in response to the energy picked up by said inductors, and another circuit means including said preselected position of the switch to couple said load winding to said control terminals to operate the train control apparatus by such current supplied to the load winding.

13. In combination with train carried train control apparatus tuned sharply to resonance at a preselected relatively high frequency and connected to designated control terminals of an equipment box housing such train control apparatus, trackway means to supply to the rails of a track section alternating current of a preselected relatively low frequency coded at a given

code rate, inductors mounted on the train in inductive relation to the rails to pick up energy in response to such coded low frequency alternating current when the train occupies said section, a train carried adapter including a rectifier and an electron tube oscillator operative to create oscillations of said relatively high frequency, circuit means to connect said inductors to the control grid of said tube through said rectifier to vary the potential of said grid with respect to the cathode of the tube in step with the code rate of the low frequency energy picked up by the inductors and cause said tube to assume oscillating and non-oscillating conditions in step with said code rate, and circuit means to couple the plate circuit of said tube to said control terminals to cause operation of said train control apparatus by the oscillations created by said tube.

14. In combination with train carried train control apparatus tuned sharply to resonance at a preselected relatively high frequency and connected to designated control terminals of an equipment box housing such train control apparatus, trackway means to supply to the rails of a track section alternating current of a preselected relatively low frequency coded at a given code rate, inductors mounted on the train in in-

ductive relation to the rails to pick up energy in response to such coded low frequency alternating current when the train occupies said section, a train carried adapter including a rectifier, a resistor, an electron tube oscillator and an output winding; said resistor interposed in the grid circuit of said tube and said output winding coupled to the plate circuit of said tube, said tube operative to create oscillation of said relatively high frequency but normally biased to a non-oscillating condition, circuit means including a given position of said switch to connect said inductors across said resistor through said rectifier to create a voltage drop across the resistor in step with the code of the energy picked up by said inductors due to said low frequency current, said resistor connected to said grid so as to cause said tube to oscillate at the code rate of said voltage drop and cause an electromotive force of said code rate to be created in said output winding, and circuit means including said given position of the switch to connect said output winding to said control terminals for operation of the train control apparatus by the electromotive force thus created in the output winding.

PAUL N. BOSSART.
